EXPLOSIVE COMPOSITION FOR
DETONATING RIVETS

Phokion Naoúm, Leverkusen-Schlebusch, Germany, assignor, by mesne assignments, to E. I. du Pont de Nemours & Co., Wilmington, Del.

No Drawing. Application June 28, 1939, Serial No. 281,737. In Germany July 14, 1938

2 Claims. (Cl. 52—1)

Riveting methods have already frequently been proposed in which the formation of the securing head is effected by detonation or explosion by means of explosive charge introduced into an interior chamber in the rivet shank. More particularly as regards the deposition of the explosive mass and the ignition thereof, many ways and possibilities have been explored in this connection. The result of these have proved 5 the difficulties involved in carrying out the proposals and severely limited these possibilities.

Since in the case of rivets we are dealing usually with very small, or somewhat small articles, the explosive charge which is to effect the necessary deformation can of course be only small. On the other hand, however, it is necessary that the explosive in question detonates with sufficient velocity in order to permit the deformation necessary for forming a tightly sitting locking head to take place, since a certain shattering is necessary herefor which amongst other things is conditioned also by the rate of interaction of the explosive. However, the velocity with which 20 particularly small quantities of explosive become converted is dependent to a great extent on the nature of the ignition. A high rate of conversion can be imparted to small quantities of not particularly sensitive explosives by means of a suitable initial ignition, whilst if the explosion 25 of the explosive substance in question is to be brought about simply by sudden heating, either correspondingly large quantities of explosives must be employed or the explosives used must according to its category be particularly sensitive and must approximate in its properties to the so-called initial explosives, which detonate even 30 in minimum quantities with great violence in contact with a flame or with a hot object and with a detonation velocity approximating more 35 or less to the theoretically possible maximum.

In addition there is the effect of an enclosure or a tamping of the small quantity of explosive which can be employed. It is known that such a tamping or a rigid enclosure raises the explosive action and will be of great influence on 40 the velocity of conversion and the explosion pressure which develops just in the case of the small

quantities of explosive which here come into question.

In many cases it has proved to be desirable, bearing in mind the metal material of the rivets, to avoid a tamping since the tamping material being ejected during the explosion may scratch or tear the metal, which may give rise to subsequent corrosion thereof. Consequently only those explosives have been found to be suitable 5 which are sufficiently sensitive to undergo conversion with sufficient velocity without tamping. In addition there is the fact that the use of a special initial ignition complicates the method in an impossible manner, so that only those explosives appear to be suitable which detonate 10 with sufficient shattering power even in small quantities by flame ignition or sudden heating to their ignition point.

If the ignition is to be effected by rapid heating of the rivet, which appears to be convenient 20 and advantageous in many respects, the further requirement must be imposed upon the explosive to be used for charging the rivet that it detonates at the lowest possible temperature, but in any case at a temperature which can exert no unfavourable influence on the metal of naturally aged rivets and so removes the necessity of having 25 to heat the rivets to too high a temperature.

An explosive which conforms to all these requirements has been found in hexamethylene-triperoxide-diamine, the interaction product of hydrogen peroxide on hexamethylene-tetramine. This substance detonates on heating to 140° C. and with sufficient shattering power even in 30 small quantities and without tamping, which shattering power can be reduced in intensity 35 as desired or required by addition of inert substances.

What I claim is:

1. An explosion rivet containing an explosive 40 composition adapted to expand the same comprising hexamethylene-triperoxide-diamine.

2. An explosion rivet containing an explosive composition adapted to expand the same comprising hexamethylene-triperoxide-diamine disposed in a cavity in the shank of said rivet. 45

PHOKION NAOÚM.
